UNITED STATES PATENT OFFICE.

RUDOLPH A. RIEK, OF RHINELANDER, WISCONSIN.

SHIELD FOR REFRIGERATING UNITS.

Application filed March 28, 1927. Serial No. 179,052.

This invention relates to a shield adapted to be positioned in front of a refrigerating unit supported within a casing of the refrigerator type.

5 Heretofore it has been the practice to bolt in front of a refrigerating unit a metal plate designed to conceal practically all portions of the unit except that part containing the ice tray or trays. Inasmuch as frequent de-
 10 frosting operations must be carried on in order to render the refrigerating unit effective, it has been found extremely difficult or unhandy to remove the shield in order to give proper access to the unit. Furthermore
 15 each time any adjustment or repairs to the unit are found necessary this same shield must be unfastened and removed. This operation soon results in defacement of the porcelainized metal used in the construction of
 20 the shield, this defacement being in the nature of inadvertent bending of the metal, chipping of the porcelain finish, etc.

It is an object of the present invention to overcome the foregoing objections by pro-
 25 viding a shield which can be easily placed in or removed from position without the use of special tools and without requiring the services of a skilled mechanic.

It is also an object to provide a structure
 30 which can be placed in and removed from position without danger of scarring or otherwise injuring the same.

With the foregoing and other objects in view which will appear as the description
 35 proceeds, the invention resides in the combination and arrangement of parts and in the details of construction hereinafter described and claimed, it being understood that changes in the precise embodiment of the
 40 invention herein disclosed may be made within the scope of what is claimed, without departing from the spirit of the invention.

In the accompanying drawings, the preferred forms of the invention have been
 45 shown.

In said drawings,

Figure 1 is a front elevation of a portion of the casing of a refrigerating unit, a shield such as constitutes the present invention
 50 being shown assembled therewith in front of the unit.

Figure 2 is an enlarged transverse section through the shield and the adjacent portions of the casing.

55 Figure 3 is a perspective view of the shield.

Figure 4 is a perspective view of a modification thereof.

Figure 5 is a perspective view of another form of the device, parts being broken away.

Referring to the figures by characters of reference A designates a portion of the casing of a refrigerating unit, said unit being indicated at B. This unit includes the usual ice trays C.

For the purpose of closing the space sur-
 65 rounding the unit and concealing all portions of the unit except the trays and adjacent parts, a shield such as constitutes the present invention is mounted within the casing A in front of the unit. This shield is formed in
 70 a single sheet of porcelainized metal and includes the shield 1 per se and side wings 2. An opening 3 is provided in the shield 1 through which the trays are exposed when the shield is set up for use and the top and
 75 bottom of the shield are stiffened by back-
 wardly extending flanges 4 provided throughout the width of the shield.

The shield 1 is of substantially the same width as the compartment D in which the unit
 80 B is mounted. The entire shield with its wings is resilient and when the shield is made to fit snugly within the compartment the wings 2 will press laterally against the walls E of the compartment as shown particularly
 85 in Figure 2. If desired the shield can be retained in place by providing outturned longitudinal flanges 5 along the front edges of the wings 2, these flanges being adapted to spring laterally into grooves or rabbets F
 90 formed in the wall of the door opening G. Thus when the door H is open the porcelainized metal shield will present an attractive appearance in that it will completely conceal the space above, below and at the sides of
 95 the unit and only expose that portion of the unit containing the trays C. Should it be desired to remove the shield it merely becomes necessary to grasp the upper and lower edges thereof located above and below the door
 100 opening and pull the wings toward each other to spring the flanges 5 out of the grooves or rabbets. When replacing the shield the flanges will snap into place.

It is to be understood that it is not necessary to use the flanges 5 because, if desired, the wings 6 of the structure shown in Figure 4 can be sufficiently stiff to support the shield by frictional contact with the walls E. Another modification of the shield has been illus-
 105

trated in Figure 5 wherein the resilient wings 7 are provided in their lower edges with short notches 8 while longer notches or grooves 9 are provided in their upper edges. Studs 10 5 can be arranged on the walls E of the compartment D and by sliding the shield upwardly with the upper studs in the grooves 9 the notches 8 can be brought to position above the lower studs 10 and the shield then lowered 10 into engagement with the studs without withdrawing from engagement with the upper studs. Consequently the shield will be held firmly and cannot be detached without first lifting it out of engagement with the lower 15 studs and then swinging it forwardly and lowering it from engagement with the upper studs.

Obviously by providing a resilient shield detachably mounted in the manner described 20 access to the unit for all purposes can be had more readily than where a shield is secured in place by means of screws or the like. Furthermore the danger of marring the shield through constant removal and replacement is 25 reduced to the minimum.

What is claimed is:

1. A shield for refrigerating units in refrigerator casings including a one-piece sheet of porcelainized metal bent to provide an intermediate or shield portion and wings at the 30 sides of said portion, there being an opening in the intermediate or shield portion for the passage of the ice tray of a refrigerating unit.

2. The combination with a casing having 35 a compartment therein and a refrigerating unit supported in the compartment, of a porcelainized metal shield in front of the unit and within the compartment and forwardly

extending wings at the sides of the shield for engagement with the walls of the compartment, said shield having an opening for the passage of an ice tray of the unit. 40

3. The combination with a casing having a compartment therein and a refrigerating unit in the compartment, of a porcelainized metal shield in the compartment in front of the unit, forwardly extending porcelainized metal wings integral with the shield, said wings frictionally engaging the walls of the compartment to support the shield removably, 45 there being an opening in the shield for the passage of an ice tray of the unit. 50

4. The combination with a casing having a compartment therein and a refrigerating unit in the compartment, of a one-piece porcelainized metal shield removably mounted in the compartment for partly concealing the unit, said shield having resilient side wings frictionally engaging opposed walls of the compartment, 55 there being an opening in the shield for the passage of an ice tray of the unit. 60

5. The combination with a casing having a compartment therein and a refrigerating unit in the compartment, of a one-piece porcelainized metal shield removably mounted in the compartment for partly concealing the unit, 65 there being an opening in said shield for the passage of an ice tray of the unit, said shield having resilient side wings frictionally engaging opposed walls of the compartment, 70 and interengaging means upon the wings and compartment walls for holding the shield in position.

In testimony that I claim the foregoing as my own, I have hereto affixed my signature.

RUDOLPH A. RIEK.
